UNITED STATES PATENT OFFICE.

CHARLES R. McDONALD AND ALBERT E. BEVAN, OF AKRON, OHIO.

LIQUID-DISPENSING APPARATUS.

Application filed December 5, 1923. Serial No. 678,537.

Our invention relates to liquid-dispensing apparatus and particularly to apparatus of this character designed for the dispensing of soft drinks, cream for coffee, syrups, etc., in 5 restaurants, soft drink parlors, soda fountains, etc., carrying on a retail trade. The objects of the invention are to provide apparatus of this character which may be economically built, easily and accurately operated, which shall dispense at each operation substantially the same amount of liquid, in which the liquid may be kept cool and refreshing, and which shall be satisfactorily sanitary.

15 Our invention also relates to apparatus of this character from which the drip of the dispensed liquid shall be eliminated.

The annexed drawings and the following description set forth in detail certain means 20 embodying our invention, such means constituting, however, but one of the various forms in which the principle of the invention may be applied.

In said annexed drawings:

25 Figure 1 represents a vertical longitudinal section of our improved apparatus, taken in the planes indicated by the line I—I, Figures 2 and 5;

Figure 2 represents a plan section, taken in 30 the planes indicated by the line II—II, Figure 1;

Figure 3 represents a fragmentary front elevation, taken from the plane indicated by the line III—III, Figure 1;

35 Figure 4 represents a section similar to Figure 1, but showing the scoop or bucket in discharging position, one of the upper positions of the scoop and bucket being also shown in dot and dash lines just previous to 40 the tilting of the bucket;

Figure 5 represents a vertical transverse section, taken in the planes indicated by the line V—V, Figure 1; and

45 Figure 6 represents a front elevation, taken from the plane indicated by the line VI—VI, Figure 4.

Referring to the annexed drawings in which the same parts are indicated by the same respective ordinals in the several views, 50 we indicated a main casing by the ordinal 1 having an upper cover 2 through which the liquid to be dispensed may be poured for filling a liquid reservoir 3 separated from an ice chamber 4 by a partition 5, said ice chamber 4 being provided with an upper cover 6 for a filler opening, and a drain 7. The res-

ervoir 3 is formed with a well 8 from which is scooped by a bucket 9 portions of the liquid 10 which are intended by the lifting and tilting of the bucket 9 to be discharged 60 through the case opening 11 into a suitable serving receptacle such as a glass or cup held by the operator adjacent to and exteriorly of the opening 11. This raising and dumping of the bucket 9 is effected by the operator 65 when the pivoted cover 12 adapted to close the opening 11 is lifted by the operator to uncover said opening 11. The actual connection between the cover 12 and the bucket so as to actuate the latter upon the movement 70 of the cover 12 is as follows; a lug 12' is secured to the inner face of the cover 12 and pivoted to this lug is a link 13 running back substantially to the rear of the chamber 3 and connected at its rear end to a short rearwardly-extending arm 14 whose other and front end is fixed to a transverse shaft 15. Also fixed to this shaft 15 is one end of a lever or arm 16 formed at its other end with a U-shaped member having arms 18 and 18' 75 within journals formed in which are pivoted trunnions 19 extended outwardly from opposite sides of the bucket 9. The forward edge of the mouth 20 of the bucket 9 is adapted to travel in a trough 21 forming a guide for the movement of the bucket from the filling position, shown in full lines in Figure 1, to the dumping position, shown in full lines in Figure 4. The comparative length of the bucket lever 16 with the distance from the opening 80 11 to the shaft 15 and the comparative heights of the shaft 15 and the bottom edge of the opening 11 are such as to cause the bucket 9 just before reaching its extreme upper position to be positively dumped by the 85 upward lifting of the rear of the bucket 9, as plainly shown in Figure 4. It is evident that the dropping or closing of the cover 12 will effect through the elements 13, 14, 15 and 16 the realignment of the bucket and the transfer of the same to the lower position shown 90 in Figure 1. The actual operation of the cover 12 may be effected by power means or manually in any suitable manner and we have shown as one example of the same a handle 95 100 105 110 115 secured to the cover 12 and having a hand grip 23. As plainly shown in Figure 1, the filler cover 2 is pivoted at its front end upon a pin 24 passed transversely through the lower portion of the opening 11 and secured at its ends to two forwardly projecting elements 25 secured to the casting 1 and which

serve to define the lower side walls of the opening 11. When the cover 2 is lifted to fill the chamber 3, the discharge opening cover 12 which is pivoted at its upper end 26 to the cover 2 is also lifted and this movement of the cover 12 will bring the bucket 9 and connected elements into the position shown in dot and dash lines, Figure 1, which positions will also help to explain the operative connection of the cover 12 and bucket 9.

Referring to the form of bucket shown by applicants, it is particularly adapted for the dispensing of cream for coffee, etc., in which operations, of course, only a small part of the cup or receptacle is filled with the dispensed liquid so that there is little liability of any slopping occurring. In this form of bucket it will be noted that the discharge mouth is provided adjacent one end of the bucket, that the charge chamber is positioned at the opposite end of the bucket and that the filler opening 9' is disposed intermediate the charge chamber and the discharge port. It will be evident that the size of the charge will be determined by the location of the wall 36 defining the lower line of the filler opening. In other words, by cutting the filler opening so that the wall 36 is higher or lower, the size of the charge will be varied, assuming that the diameter of the bucket is maintained constant. The object of this construction is to make buckets for charges of varying sizes, the buckets to have a uniform diameter. Therefore, if it is desired to change the size of the charge, a bucket is substituted for the one in use which shall have a filler opening 9' cut at the proper height, when the bucket is held in vertical position, to provide the size of the charge desired. It is evident that when the buckets are held in vertical position, all of the contents thereof above the line 36 will run out. We plainly show in Figures 1, 2, 4, and 5 means for readily replacing the buckets 9. It would be impracticable, of course, to spring the yoke arms 18 and 18' sufficient to remove the bucket 9, so that we make one of these arms 18' a readily removable member from the arm 18 and also readily again attached. This construction is plainly shown in Figure 5. Now, inasmuch as all of the buckets 9 are of uniform diameter, the size of the charge being determined by the position of the wall 36, it is evident that the one bucket support 16—18—18' will serve for buckets holding all of the desired

sizes of charges, and that these buckets may be quickly and conveniently changed.

What we claim is:

1. A liquid-dispensing apparatus, the combination of a liquid receptacle formed with a discharge opening; a bucket; a support in which said bucket is pivoted; a movable cover for said discharge opening; means for opening and closing said cover, said last-mentioned means being connected to the bucket-supporting means so as to effect the raising of said supporting means as the cover is being opened, and the lowering of said supporting means as the cover is being closed, and means for tilting the bucket to discharge through said opening when the cover has been fully opened, said tilting means realigning the bucket as the latter is again lowered.

2. In liquid dispensing apparatus, the combination of a liquid receptacle formed with a discharge opening; a bucket; an inclined guide in which said bucket is adapted to travel; a forked support in which said bucket is pivoted; means for tilting the bucket; a pivotally-mounted cover for said discharge opening; and means for opening and closing said cover, said last-mentioned means being connected to the bucket supporting and tilting means so as to effect the raising of said supporting means and the tilting of the bucket to discharge through said opening when the cover is opened and the realigning of the bucket and the lowering of the latter while said cover is being closed.

3. In liquid dispensing apparatus, the combination of a liquid receptacle formed with a side discharge opening; a bucket; a forked support in which said bucket is pivoted at one end; a shaft journalled in the walls of said receptacle, the other end of the bucket support being secured to said shaft; a pivotally-mounted cover for said discharge opening; a rearwardly-extending arm secured to said shaft; and a link pivotally connected to said cover and to said arm, the length of said bucket support being less than the distance between said discharge opening and said shaft so that the bucket is tilted when the forked end of its support is raised above said discharge opening.

Signed by us this 5th day of November, 1923.

CHARLES R. McDONALD.
ALBERT E. BEVAN.
